UNITED STATES PATENT OFFICE.

ANSON SEARLS, OF NEWARK, NEW JERSEY, ASSIGNOR TO THE SEARLS-RANDALL COMPANY, OF SAME PLACE.

ARM-RAIL FOR SLEIGHS.

SPECIFICATION forming part of Letters Patent No. 407,905, dated July 30, 1889.

Application filed April 19, 1889. Serial No. 307,768. (No model.)

To all whom it may concern:

Be it known that I, ANSON SEARLS, a citizen of the United States, residing at Newark, in the county of Essex, State of New Jersey, have invented certain new and useful Improvements in Arm-Rails for Sleighs; and I do hereby declare that the following is a full, clear, and exact description of the invention, which will enable others skilled in the art to 10 which it appertains to make and use the same.

My invention relates to arm-rails for the sides of sleigh-seats; and it consists in a rail made in one piece and adjustable by means of a stud and socket and held by a bracket that 15 spans the molding of the panel, and may be put on after a sleigh is finished; also, of a cap-finisher, all as hereinafter fully described.

The drawings herewith show, in Figure 1, a side view, and in Fig. 2 the handle end of rod 20 A. Fig. 3 is a view of the cup C, Fig. 4 of the bracket B, Fig. 5 of the stud D, and Fig. 6 of the same threaded at F. Fig. 7 is a top view of all the parts, showing hole f in bracket B; and Fig. 8 a modified form of arm H. Fig. 25 9 shows a sleigh with the arm-rail A attached.

The rail A, made of drawn brass rods or other suitable material, has a handle end c, flattened out at c, and provided with a hole d, and is preferably covered by a concavo-convex 30 cup C, by which it is attached to the side of a sleigh with a screw or bolt. The middle of the rail A is held by a bracket B, and at the back end by a socket E and threaded stud D. The rail may be bent to any desired form to 35 fit sleighs of various styles, and a handle formed of any pattern between the end c and bracket B, and polished or plated, as desired. This is done from a drawn rod in distinction from those heretofore forged and fitted to 40 sleighs or cast to fit the same, thereby reducing the cost.

The bracket B is adapted to be fastened to the top edge of the sleigh-panel and to the side of the same after the sleigh is trimmed 45 and finished, and to span the usual molding that finishes the side of a sleigh at the seat. At B, Fig. 7, it is perforated to receive the rail A, and is provided with an arm H, that is attached to the top of the sleigh-panel by a 50 screw in hole f. From B, Fig. 4, it extends

down and inward and terminates in a boss g, that may be attached to the side of a sleigh by a screw or bolt.

As a modification, the screw used in hole f may be a pin j, Fig. 8, and enter the top of the panel, while the screw at g holds the bracket 55 down firmly.

The hold of the arm H on the panel is improved by the catch i, that may enter the top of the panel or set down inside of it, grasping 60 the panel so it cannot be torn off by splitting out a piece from the side by the screw or pin j. The angle formed by arm H to B and extension to g will span the usual molding used 65 on sleigh-panels.

The form of bracket B may be modified as desired. By the arm H, attached to the top of the panel at f, the trimming is not disturbed. The bracket B is supported by the brace from B to g, Fig. 4, and also spans the molding and 70 sets the rail A out a proper distance from the panel, and may be put on any time after the sleigh is finished and at any desired part of rail A. The end holder, Fig. 5, has a socket E and receives the threaded stud F on plate 75 D at right angles to perforation h. After the rail A is otherwise attached to the sleigh the surplus, if any, at e may be cut off by a bolt-cutter or any well-known means and the socket E put on and firmly attached by screwing up the stud F at i, Figs. 1 and 7. The plate D is then screwed or bolted to the sleigh. By this means rails may be made extra long 80 and cut or adjusted to the varying sizes of sleighs, and a durable and ornamental finish 85 made to the back end, setting the rail A out from the sleigh at e a proper relative distance to the other fastenings. This rail A may be plated and the parts C, B, and E made black, or the reverse, to secure an ornamental result. 90

Where an exact ordered length is desirable, the end finishers D and E may be dispensed with, and the back end at e may be finished with a hole d, as at c, or with a cup C, covering the same and held with a bolt or screw. 95

As a modification, the rail A may be secured at c and e by dispensing with the cup C and placing the bolt or screw directly through the rail A, but the finish will not be as desirable, and when iron is used the end may rust after 100

plating unless covered by the cup C; but without the plate and stud D and socket E the rail is not adjustable, so as to be of commercial value as an article of manufacture for sale to the trade for any size of sleigh.

Having described my invention, I desire to secure by Letters Patent—

1. A bracket having an arm H and extension g, adapted to span a sleigh-panel molding, in combination with a sleigh-arm rail, substantially as set forth.

2. A bracket provided with a catch i, in combination with a sleigh-arm rail, substantially as set forth.

3. The cup C, in combination with a sleigh-rail A, substantially as and for the purpose set forth. 15

4. The combination of a socket E and stud F with a sleigh-rail, substantially as and for the purpose set forth. 20

5. The combination of the rail A, bracket B, and cup C with end finishers D and E, as and for the purpose set forth.

ANSON SEARLS.
